No. 792,794.

PATENTED JUNE 20, 1905.

J. ROGERS.

FIRE EXTINGUISHING BUILDING CONSTRUCTION.

APPLICATION FILED AUG. 30, 1904.

UNITED STATES PATENT OFFICE.

JOHN ROGERS, OF PERRY, IOWA.

FIRE-EXTINGUISHING BUILDING CONSTRUCTION.

SPECIFICATION forming part of Letters Patent No. 792,794, dated June 20, 1905.

Application filed August 30, 1904. Serial No. 222,727.

To all whom it may concern:

Be it known that I, JOHN ROGERS, a citizen of the United States, residing at Perry, in the county of Dallas and State of Iowa, have invented certain new and useful Improvements 5 in Fire-Extinguishing Building Constructions, of which the following is a specification.

The aim of this invention is to provide a dwelling, office, or other building with an apparatus embodying, essentially, a special arrangement of pipes and wall construction enabling the building to be thoroughly drenched, either wholly or in any ascertained part thereof, in the event of fire.

15 As premised above, the invention resides particularly in the construction of the walls or ceilings of the building whereby water may be fed through the water-pipes adjacent into any part of the building as governed by the 20 use of suitable valve mechanism.

For a full description of the invention and the merits thereof and also to acquire a knowledge of the details of construction of the 25 means for effecting the result reference is to be had to the following description and accompanying drawings.

While the essential and characteristic features of the invention are susceptible of modification, still the preferred embodiment of the 30 invention is illustrated in the accompanying drawings, in which—

Figure 1 is a sectional view showing building construction embodying the essential features of the invention. Fig. 2 is a detail perspective view, partially in section and partially broken away, showing more clearly the manner of attaching the inner and outer plates comprised in the ceiling or wall construction of the building.

40 Corresponding and like parts are referred to in the following description and indicated in both the views of the drawings by the same reference characters.

It is designed that the building be of any 45 construction desired from an architectural standpoint, and water is supplied from the water-main 1 through a series of inlet-pipes 2, leading off to the various parts of the building, so as to supply the water in order to extinguish the fire by flooding the rooms or

apartments. The inlet-pipes 2 have the supply of water thereto governed by suitable valves 3, the latter being located adjacent the water-main and adapted to govern the flow of the water through the individual pipes leading off to the various floors of the building or the rooms thereof. For instance, if it is desired to flood the rooms upon a single floor only of the building, the valve 3 of the pipe 2 leading off to said floor is opened, so that this floor only will be flooded in the event of fire in said portion of the building. The supply of water from the main to the pipes 2 may be governed by a main valve 4, and it will be understood that the various valves 3 and 4 55 may be located within the building or outside thereof, as determined by the usual considerations. In tropical climates the valves may be inclosed in a suitable casing entirely outside of the building, so as to be readily operated 60 by a passer-by who might happen to note that said building had taken fire. In cooler climates, however, the valves 3 and 4 and the pipes for conveying the water are preferably located within the building, so as to obviate 65 any likelihood of freezing. It is also contemplated within the scope of the invention to utilize any number of the pipes 2, and instead of said pipes leading off to the floor of the building, as illustrated in the drawings, said 70 pipes may extend to any room or part of the building desired, thus enabling the drenching of any room without damaging the adjacent parts of the building and the furnishings thereof. The valves governing the pipes 2, 75 which lead to the various rooms, would have suitable designations to indicate just what room the water-inlet pipe extended to. A valve having the letter "K" would govern the flow of water to the kitchen, the one having the letter "D" would indicate that the supply-pipe governed thereby extended to the dining-room, and so on.

The means whereby the water from the inlet-pipes 2 is directed into the various parts 85 of the building in such a manner as to thoroughly drench the same consists, essentially, in the peculiar structure of the walls or ceilings, and, describing the last feature specifically, it will be noted that the ceilings of the 90

building, as shown in the drawings, are preferably made of spaced inner and outer plates 5 and 6, respectively. The plates 5 and 6 are peculiarly attached and are supported by the 5 usual I-beams 7 commonly employed in the ordinary construction of buildings. The plates 5 and 6 are spaced, as mentioned above, the spaced portion being located centrally thereof, as shown at 8. In order to attach the 10 plates 5 and 6 together and to secure the same in position, so that the outer plates 6 will comprise the ceiling or wall surface, each of the outer plates 6 is provided with a plurality of lugs 9, projected from the inner sides thereof, said lugs having angular extensions 10 and being adapted to be passed through openings 11 in the inner plate 5. The openings 11 of the inner plates 5 are somewhat elongated in order that the lugs 9 may pass therethrough 15 and give a slight lateral movement by similar movement of the plate carrying the same in order to cause the extensions 10 of the said lugs to engage with the inner side of the plate 5, to which said plate 6 may be attached. The 20 lugs 9 thus support the plates 6, suspended from the plate 5, and these plates 6 are designed to be of any ornamental formation and can be made of art metal or the like in order to promote the decorative effect of the ceiling 25 or wall construction, as the case may be. The inner plates 5, which curve between their ends in order to form the space 8, have their edge portions spaced from the outer plates 6, as shown at 5^a, and the spaced edge portions of 30 the respective plates 5 and 6 receive the oppositely-disposed flanges of the I-beams 7, thereby affording a connection between the I-beams and the spaced parts 5 and 6, whereby the latter are held in position. The adjacent 35 plates 6 are arranged with their outer surface flush, and these plates are provided with a plurality of apertures 12, through which the water fed from the inlet-pipes 2 passes in flooding or drenching the building. The apertures 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 Having thus described the invention, what is claimed as new is—

1. In construction of buildings or the like, ceiling or wall structure embodying inner and outer plates spaced from each other centrally thereof to form a water-chamber, lugs projected from the outer plate and engaging the inner plate to attach same together, water-inlet pipes communicating with the space between the plates, the outer plate being apertured for egress of the water from the water-chamber aforesaid.
2. In construction of buildings or the like, wall structure embodying inner and outer plates spaced centrally from one another and also spaced at the edges, supporting-beams

having portions received between the spaced edges of the plates aforesaid, the inner plate being provided with elongated openings, lugs projected from the outer plate and passing through the elongated openings of the inner plate, engaging extensions projected from the lugs, and water-supply pipes communicating with the space between the central portions of the plates.

In testimony whereof I affix my signature in presence of two witnesses.

JOHN ROGERS. [L. S.]
